(57) **CLAIM**

The ornamental design for a case for thermometer as shown and described.

DESCRIPTION

FIG. 1 is a front, right and top perspective view of a case for thermometer in a closed state, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view of the case for thermometer in an open state; and,

FIG. 10 is another rear, left and bottom perspective view of the case for thermometer in an open state.

The broken lines depict portions of the case for thermometer that form no part of the claimed design.
